LADLE

Henry E. McWane and Hugh K. McGavock,
Lynchburg, Va.

Application October 1, 1942, Serial No. 460,438

7 Claims.

(Cl. 22—57)

The present invention relates to casting and more particularly to a method and apparatus for introducing molten metal into the casting cavity of top gated permanent molds under controlled conditions.

Top gating of molds presents several distinct advantages, probably the most important of which is the great reduction in sprue loss, but heretofore difficulty has been experienced in producing satisfactory castings in top gated metal molds due primarily to the method of hand pouring from the conventional foundry ladle. Due to the parabolic path of the metal flowing from a hand ladle and the human element involved in hand pouring, it is practically impossible to prevent the metal contacting the cool walls of the gate where it freezes, constricting and sometimes entirely closing the gate. Then, again, the pouring gate and the velocity of the metal entering the mold will vary in pouring a number of castings which will result in a dissimilarity in their metallic structure.

We have found, that by directing the stream of molten metal axially of the gate and by controlling its velocity and restricting its cross-sectional area to a size less than that of the gate, as disclosed in our copending application Serial No. 460,566 filed Oct. 2, 1942, the metal may be introduced into the mold without coming in contact with the walls of the gate. By such method of pouring we are enabled to definitely control the metal with the result that a better casting is produced and that successive castings will be similar. An additional advantage of this controlled pouring is that it permits the use of a cooler metal and therefore quicker setting in the mold. This not only prevents the formation of large fins but permits the casting to shrink, at least partially, during the pouring operation thereby reducing the amount of shrinkage strains.

In its broadest sense, our invention is directed to the idea of measuring a predetermined amount of molten metal from a supply in a foundry ladle into a supplementary ladle, operatively associated with a casting machine provided with a separable, top gated mold, then introducing the metal from the supplementary ladle into the mold in such a way that the metal enters the mold axially of the gate and in a stream of less cross-sectional area than that of the gate.

In its more limited application, as disclosed in the specific embodiment shown herein, we provide an enclosed cylindrical ladle of refractory material enclosed in a heat insulating casing.

Spaced in its cylindrical wall are a substantially radial filling orifice for introducing molten metal into the ladle, an elongated discharging duct arranged at right angles to the filling orifice and a sighting aperture for visually determining the amount of metal being poured into the ladle.

The ladle is rotatable on axial trunnions from a filling and nonpouring position to a pouring position in which the discharge orifice will lie in the axis of the mold gate. A latch mechanism, releasable by the closing action of the mold, normally maintains the ladle in its non-pouring position. Upon release of the latch an overbalance weight rotates the ladle to its pouring position, its movement being retarded by a resilient damping device. A lost motion link, operable by the opening action of the mold, connects with an eccentrically located pin carried by the ladle to return it to its non-pouring position. During the rotation of the ladle from its non-pouring to its pouring position, metal flows from the interior of the ladle and through the elongated discharge duct before discharging from the ladle. This is an important feature of the invention as it permits the ladle to position itself with its pouring orifice in a vertical pouring position before the metal discharges.

One of the principal objects of the present invention is to provide a method and apparatus for introducing a predetermined amount of molten metal into top gated molds while controlling the direction and size of the stream of metal with respect to the mold gate.

Another important object is to provide a method and apparatus for introducing a predetermined amount of molten metal into top gated molds by directing a stream of metal of smaller cross-sectional area than the mold gate in a direction axially of the gate.

Yet another object is to provide a method and apparatus for introducing molten metal into top gated molds by the rotation of a ladle in which a predetermined amount of metal has been admitted and from which the discharge of metal is delayed during rotation of the ladle.

A further object of this invention is to provide a ladle for pouring molten metal into separable molds which comprises means to maintain the ladle in a non-pouring position while the mold is open, releasing the maintaining means upon closing of the mold to allow the ladle to move to its pouring position and returning the ladle back to its non-pouring position upon reopening of the mold.

A still further object is to provide a ladle of the character above described in which friction between moving parts has been reduced to a minimum to assure easy operation of the ladle.

A still further object is to provide a pouring ladle of the above type which is simple and economical in its construction and upkeep, yet which is efficient in its operation and effective in its results.

Other objects and advantages will become readily apparent to those skilled in foundry practice from the following detailed description and by reference to the accompanying drawings which represent only a preferred embodiment of our invention.

In the drawings on which like characters of reference are employed to represent like parts throughout:

Figure 1 is a side elevation of a casting machine with our ladle in operative association therewith, showing the mold open and the ladle in its non-pouring position;

Figure 2 is a plan view of the apparatus illustrated in Figure 1;

Figure 3 is a fragmental sectional view taken along the line 3—3 of Figure 2, looking in the direction of the arrows;

Figure 4 is a fragmental sectional view taken along the line 4—4 of Figure 2, looking in the direction of the arrows;

Figure 5 is a view similar to Figure 3 but showing the parts in their pouring position;

Figure 6 is a view similar to Figure 4 but showing the parts in pouring position;

Figure 7 is a transverse sectional view taken along the line 7—7 of Figure 4, looking in the direction of the arrows;

Figure 8 is a transverse sectional view taken along the line 8—8 of Figure 6, looking in the direction of the arrows;

Figure 9 is a cross sectional view taken along the line 9—9 of Figure 2, looking in the direction of the arrows; and

Figure 10 is a fragmental sectional view taken along the line 10—10 of Figure 2, looking in the direction of the arrows.

Referring more particularly to the drawings there is illustrated a casting machine having a frame 1 comprising a pair of horizontal tracks 2, one end of each of which is attached to an end plate 3 which supports a stationary mold block 4. A complementary mold block 5 is carried by a plate 6 slidably mounted on the tracks 2. The movable block 5 is adapted to be reciprocated into and out of engagement with the stationary block 4 by means of a pneumatic motor 7. When the mold blocks 4 and 5 are in operative engagement they form a casting cavity 8 which has communicating therewith a gate 9 extending vertically to the top face of the mold. Detailed description of the construction and operation of such a casting machine is included in the copending application of Henry E. McWane, Serial No. 422,912, filed December 13, 1941, and further description is not thought necessary for purposes of the present application.

The upper surface of the end plate 3 has adjustably attached thereto a pair of upwardly and forwardly extending brackets 10 and 11 which are provided at their extending ends with split clamping rings 12. The brackets 10 and 11 are connected and held in fixed spaced relation with each other by means of a pair of cross angles 13 and 14 attached to the brackets by suitable means such as the cap screws 15.

The pouring ladle which is designated generally as 16 comprises an enclosed refractory cylinder 17 clamped concentrically between a pair of circular end discs 18 and 19 by means of draw bolts 20. The end discs 18 and 19 are of slightly larger diameter than the refractory cylinder 17 and a heat insulating disc 21 of asbestos or other suitable material is interposed between each end of the cylinder 17 and the end discs. Heat insulant 22 such as asbestos cement is also molded around the cylinder as shown in Figures 4 and 7 to prevent heat loss from the ladle.

Each of the plates 18 and 19 is provided with a concentric shouldered trunnion 23 on which is fitted an anti-friction bearing 24 between inner and outer retaining collars 25 and 26. The bearings 24 are held in the clamp rings 12 of the brackets 10 and 11 to permit the ladle to rotate about its axis in a definite position with respect to the mold.

The ladle, normally, is held against rotation in a predetermined position by means of a pawl 27 pivoted at its lower end as shown at 28 to the bracket 10. The upper end of the pawl 27 is urged toward the periphery of the disc 18 by means of a compression spring 29 positioned between the pawl and the cross angle 13. When the ladle is in its inoperative, or non-pouring position, as is shown in Figure 3, the pawl engages one of a series of ratchet teeth 30 formed in the edge of the end disc 18. Upon disengagement of the pawl from the teeth 30, by means to be described later, an overbalance weight 31, eccentrically attached to the end disc 19, will cause the ladle to be rotated about its axis until the offset weight abuts a stop lug 32 provided on the bracket 11. In order to retard somewhat this rotational movement and thereby minimize the stopping shock, a yieldable frictional element 33 is provided in the path of the weight 31. This friction element comprises a flat spring 34, one end of which is held by a rod 35, and then spirally wound about the rod and extended upwardly into the path of the weight. The rod 35 is rotatably mounted in the bracket 13 for adjustment of the position of the spring 34 and is adapted to be locked in adjusted position by means of a lock nut 36.

As stated, the ladle proper comprises a refractory cylinder 17. This cylinder is closed at both ends to provide a reservoir 37 for holding a supply of molten metal 38. A filling orifice 39 is provided in the cylindrical wall of the ladle slightly offset diametrically from the center line. When the ladle is in the filling position as shown in Figure 4, the filling orifice is positioned substantially vertically and when the ladle is in pouring position it is disposed horizontally and above the horizontal center line of the ladle.

The discharge duct indicated generally as 40, and which forms one of the principal features of this invention, comprises a longitudinal channel 41 formed in the cylindrical wall of the refractory block 17 and has its ends curved inwardly, as shown in Figure 8, to communicate with the interior of the reservoir 37. Intermediate its ends the channel 41 is slightly enlarged as shown at 42 to accommodate a slight overflow of metal and a pouring orifice 43 of somewhat smaller cross-sectional area than the mold gate 9 connects the enlarged portion 44 of the channel 41 with the exterior of the ladle. When the ladle is in filling position, this pouring duct 40 is disposed substantially horizontally, the lower edge of the channel 41 lying substantially in the horizontal

median plane of the ladle. When the ladle is rotated to its pouring position, however, as shown in Figure 6, the pouring duct will be vertically disposed and the axis of the orifice 43 will coincide with the axis of the gate 9. It is to be noted that the outer end of the orifice 44, that is, the end formed in the insulant 22 is somewhat larger than that portion of the orifice 43 which passes through the refractory 17, as indicated at 44, to serve the purpose of preventing the metal from freezing to the mouth of the orifice 43.

A sighting aperture 45 is also provided in the cylindrical wall of the ladle, adjacent one of the end walls of the cylinder 17, so that it will be substantially aligned with one of the inlet ends of the discharge channel 41. The volume of the reservoir 37 is such that when the surface of molten metal, poured through the filling orifice 39, is observed through the aperture 45 to reach the inner end of the channel 41, sufficient metal will have been poured into the ladle to form perfectly one casting.

In order to synchronize the operation of the ladle with the casting machine, an L shaped bracket 46 is attached to the upper face of the movable plate 6 of the machine and in alignment with the end disc 18 of the ladle. An extension 47 is provided on the horizontal portion of the L shaped bracket and has threaded into its outer end a pin 48 provided with a lock nut 49. The pin 48 is adapted to move in the path of and release the pawl 27.

Pivotedly attached to the upper end of the L bracket by means of an anti-friction bearing 50 is a rod 51 having the upper and lower surfaces of one of its ends provided with longitudinal grooves 52. This end of the rod 51 is also vertically slit and fitted with a transverse screw 53 to provide a clamp for the open end of a U shaped loop 54. The loop passes around an anti-friction roller 55 carried by a crank pin 56 eccentrically mounted on the face of the ladle disc 18, the closed end 57 of the loop being adapted to engage the roller.

The pivoted rod 51 and loop 53 form a lost motion link 58 by means of which operative connection is effected between the movable mold block and the ladle. In order to eliminate operating drag as much as possible, the distance between the arms of the loop 53 is made slightly greater than the diameter of the roller 54, as shown in Figure 10, and an adjustable counterweight 59 is provided on the opposite end of the rod 54 to effect a balance of the link 57.

In operation, molten metal is poured from a foundry ladle through the filling orifice 39 into the reservoir 37 until its level has been observed through the aperture 45 to have reached the level of the lower surface of the discharge channel 40. The casting machine is then put in operation to move the movable mold block 5 into engagement with the fixed block 4 to form the casting cavity 8 and the gate 9. Immediately prior to the mold closing, the pin 48 contacts the pawl 27 and during the final closing movement of the mold releases the pawl from engagement with the ratchet teeth 30 to allow the ladle to be moved, by means of its overbalance weight 31, to its pouring position. As the weight 31 approaches the stop lug 32 the momentum of the ladle is slightly retarded by means of the yieldable frictional element 33 to eliminate rebound from the stop 32.

Due to the elongation of the discharge duct 40 there is a sufficient delay in the efflux of the molten metal to permit the orifice 43 to position di-

rectly over the mold gate 9 before any metal is discharged from the ladle. The metal flows in a straight vertical line downward, without coming in contact with the walls of the gate 9, to fill the mold cavity 8 and enough of the gate to compensate for the setting shrinkage of the casting. After the metal has set, the mold is cracked in the manner disclosed in the above mentioned application directed to the casting machine and, 10 after the casting has cooled sufficiently to permit removal, the mold is completed, opened to discharge the casting. As the movable mold block 5 moves away from the fixed block, the end 57 of the loop 52 engages the eccentrically mounted 15 roller 55 to return the ladle to its initial filling position when the pawl 27 again engages the ratchet teeth 30 to maintain the non-pouring position until the mold again closes on the next casting cycle.

20 As stated above, metal is admitted into the reservoir 37 until its level reaches the level of the discharge duct. The amount of metal poured into the reservoir without overflowing may be varied, however, by changing the horizontal level 25 of the entrance to the channel 41. To accomplish this the lost motion link 58 may be either lengthened or shortened by means of the adjustable connection between the loop 52 and the arm 51 to effect the relative position of the entrance 30 to the channel 41 above or below the horizontal median plane of the reservoir 37. The pawl 27 will then engage another of the ratchet teeth 30 to hold the ladle in the changed filling position. Obviously, the more the channel is raised above 35 the horizontal line the more metal may be poured into the reservoir without overflowing, or, if desired the level of the channel 41 may be raised higher and the metal quantity be determined by overflow through the aperture 45.

40 While we have shown and described only a preferred embodiment of our invention we wish it to be understood that we do not confine ourselves to the precise details herein set forth by way of illustration, as it is apparent that many changes 45 and variations may be made therein by those skilled in the art without departing from the spirit of the invention or the scope of the appended claims.

We claim:

50 1. In combination with a casting apparatus having a stationary mold part and movable mold part adapted to be moved into operative engagement with the fixed mold part to provide a casting cavity and a top gate therefor, a ladle associated with the fixed mold part for rotational movement with respect thereto, a discharge opening in the ladle, and means associated with the movable mold part to effect rotation of the ladle upon movement of the movable mold part into engagement with the fixed mold part to align said opening axially with respect to said gate.

55 2. A rotatable ladle for introducing molten metal into the casting cavity of a mold having a vertically disposed top gate, a reservoir for the molten metal, said reservoir having a cylindrical wall, said wall having a substantially radially disposed discharge orifice therein for efflux of the metal, means to cause rotation of the ladle to effect axial alignment of the discharge orifice and the mold gate, and conduit means having an entrance normally above the level of the molten metal in the reservoir and connecting the reservoir with the discharge orifice, the said conduit means being disposed within said wall and having a portion thereof extending longitudinally of said

60 65 70 75

wall to delay the initial efflux of molten metal during said rotation of the ladle.

3. In a rotatable ladle for introducing molten metal into the casting cavity of a mold having a vertically disposed top gate, a reservoir for the molten metal, a discharge orifice for efflux of the metal, means to cause rotation of the ladle to effect axial alignment of the discharge orifice and the mold gate, and a channel connecting the reservoir with the discharge orifice, said channel having a length sufficient to delay initial efflux of molten metal from the discharge orifice until said axial alignment has been effected.

4. In a rotatable ladle for introducing molten metal into the casting cavity of a mold having a vertically disposed top gate, a cylindrical reservoir for the molten metal, a substantially radial discharge duct communicating with the reservoir, holding means engageable with the ladle to maintain a predetermined angular disposition of the discharge orifice, and eccentric weighted means carried by the ladle to impart rotational movement to the ladle to effect axial alignment of the discharge orifice and gate upon release of the holding means.

5. In a rotatable ladle for introducing molten metal into the casting cavity of a mold having a vertically disposed top gate, a cylindrical reservoir for the molten metal, a substantially radial discharge duct communicating with the reservoir, holding means engageable with the ladle to maintain a predetermined angular disposition of the discharge orifice and eccentric weighted means carried by the ladle to impart rotational movement to the ladle to effect axial alignment of the discharge orifice and gate upon release of the holding means, and yieldable means engageable with the eccentric weighted means to damp said rotational movement.

6. In combination with a casting apparatus having a stationary mold part and a reciprocating mold part adapted to engage the stationary mold part to form a casting cavity and a vertically disposed top gate therefor, a cylindrical ladle, means carried by the fixed mold part to mount the ladle for rotational movement, a substantially radial discharge duct in the ladle, holding means engageable with the ladle to maintain a non-pouring position thereof, rotation imparting means associated with the ladle to effect a pouring position of the ladle upon release of said holding means, and release means associated with the movable mold part to release said holding means upon movement of the movable mold part into engagement with the stationary mold part.

7. In combination with a casting apparatus having a stationary mold part and reciprocating mold part adapted to engage the stationary mold part to form a casting cavity and a vertically disposed top gate therefor, a cylindrical ladle, means carried by the fixed mold part to mount the ladle for rotational movement, a substantially radial discharge duct in the ladle, holding means engageable with the ladle to maintain a non-pouring position thereof, rotation imparting means associated with the ladle to effect a pouring position of the ladle upon release of said holding means, release means associated with the movable mold part to release said holding means upon movement of the movable mold part into engagement with the stationary mold part, and means operatively connecting the movable mold part with the ladle to effect a counter rotation of the ladle upon movement of the movable mold part away from the stationary mold part.
